(57) **CLAIM**

An ornamental design for an engine blower housing with low profile air cleaner, as shown and described.

DESCRIPTION

FIG. 1 is a perspective view of a first embodiment of an engine blower housing with low profile air cleaner showing our new design;

FIG. 2 is a top view thereof;

FIG. 3 is a rear view thereof;

FIG. 4 is a right side view thereof;

FIG. 5 is a left side view thereof;

FIG. 6 is a front view thereof;

FIG. 7 is a bottom view thereof;

FIG. 8 is a perspective view of a second embodiment thereof;

FIG. 9 is a top view thereof;

FIG. 10 is a rear view thereof;

FIG. 11 is a right side view thereof;

FIG. 12 is a left side view thereof;

FIG. 13 is a front view thereof; and,

FIG. 14 is a bottom view thereof.

The broken lines showing in the figures are for purposes of illustrating portions of the engine blower housing with low profile air cleaner (or associated components) only and form no part of the claimed design.
